UNITED STATES PATENT OFFICE.

ALBERT W. FOOTE, JR., OF BUFFALO, NEW YORK, ASSIGNOR TO JOHN HEIDER, ALBERT W. FOOTE, AND JOSEPH SCHERER, OF SAME PLACE.

DESIGN FOR A RADIATOR.

SPECIFICATION forming part of Design No. 26,569, dated January 26, 1897.

Application filed October 21, 1896. Serial No. 609,616. Term of patent 31 years.

To all whom it may concern:

Be it known that I, ALBERT W. FOOTE, JR., a citizen of the United States, residing at Buffalo, in the county of Erie and State of New York, have invented and produced a new and original Design for a Radiator-Section, of which the following is a specification, reference being had to the accompanying drawing, representing a side elevation of a radiator-section, this view being deemed sufficient to fully illustrate my design.

The leading feature of my design consists in a radiator-section having the ornamentation and shape shown in the drawing, its ornamental portions 1, in relief, extending from the upper nipple-opening 1^a in opposite directions therefrom and then a short distance downward on each opposite outer-flue side, as shown in said drawing, also the raised ornamentations 2, located at about the center of said outer portions of the section, and the ornamental portions 3, in relief, extending from the lower nipple-opening 3^a outward each way and then upward on said

outer portion. Between the two outer portions of the section is a central portion 5, in the form of a cross, which connects with the top and bottom and with each outer side. On the central-flue portion 5 are two ribs 6 and 6^a, which extend from the bottom nipple-opening 3^a to the upper nipple-opening. Extending up from the bottom of the central flue 5 a short distance is an ornamental portion 7, covering that portion between the ribs 6 and 6^a and the beveled sides on each side of it. The ornamental portion 7 extends up about one-fifth of the height of the central flue 5. The supporting-legs 4 are also covered with ornamental scrollwork in relief, substantially as shown.

I claim as my invention—
The design for a radiator-section, substantially as herein shown and described.

ALBERT W. FOOTE, JR.
